FOREIGN PATENT DOCUMENTS

EP	0951868	10/1999
WO	2015054070	4/2015

Primary Examiner — Bridget L Eland(74) *Attorney, Agent, or Firm* — Sorell, Lenna & Schmidt, LLP(57) **CLAIM**

The ornamental design for a surgical retractor, as shown and described.

DESCRIPTION

FIG. 1 is a perspective view of a surgical retractor;
 FIG. 2 is a front view of the surgical retractor;
 FIG. 3 is a side view of the surgical retractor;
 FIG. 4 is a back view of the surgical retractor;
 FIG. 5 is a side view of the surgical retractor;
 FIG. 6 is a top view of the surgical retractor; and,
 FIG. 7 is a bottom view of the surgical retractor.
